UNITED STATES PATENT OFFICE.

SAMUEL CHENEY, OF WICKEPIN, WESTERN AUSTRALIA, AUSTRALIA.

AUTOMATIC AIR-ESCAPE VALVE FOR RAILWAY-BRAKES.

1,137,575.

Specification of Letters Patent. Patented Apr. 27, 1915.

Application filed November 23, 1914. Serial No. 873,576.

To all whom it may concern:

Be it known that I, SAMUEL CHENEY, a subject of the King of Great Britain, and residing at Wickepin, Western Australia, 5 Commonwealth of Australia, have invented certain new and useful Improvements in Automatic Air-Escape Valves for Railway-Brakes, of which the following is a specification.

10 The present invention relates to railway air brakes and particularly to those of the type which are applied by the reduction of air pressure on one side of the brake piston, and it provides simple and improved means 15 for effecting a rapid discharge and consequent reduction of such air for emergency application of the brakes.

In order that my invention may be clearly understood the same will be explained with 20 the aid of the attached drawing wherein the figure represents the device in sectional elevation.

In said drawing *a* is the tubular piston rod having formed therein the small bore *b*. 25 On each end of this rod *a* is carried the large and small piston respectively as *c* and *d* of different diameters and working in their own cylinders as *e* and *f*. The small piston acts as the valve controlling the air exit 30 ports. These pistons are provided with approved packing rings as *g* and *j*.

The larger cylinder *e* is adapted to intersect screw with the small cylinder *f* as shown and cylinder *e* at its end *k* is screw threaded so 35 as to suitably connect with the train pipe by usual union or joint while the cylinder *f* by its end *m* is likewise screw threaded so as to connect with the brake cylinder in suitable manner. The small cylinder *f* is formed 40 with the radial air exit ports *n* whereby air from the brake cylinder is exhausted when the small piston *d* as shown in broken lines moves sufficiently to uncover said air exit ports. The object of the larger piston *c* is to 45 control the small piston *d* while the train pipe is charged with air for releasing brakes or while the train pipe is in "running" condition, thus holding the small piston *d* in "non-application" position, that is, to keep 50 the discharge ports *n* closed.

The pistons and their rods are tubular in order to pass air therethrough to normally keep a uniform pressure per square inch on both pistons *c* and *d* and also to feed the 55 brake cylinders with air.

The bore *b* of the piston rod is sufficiently small to permit air to feed slowly therethrough. When the pressure in the train pipe is reduced for the usual service application of the brakes, the small piston *d* will be 60 subject to a greater pressure than the opposing pressure acting on the larger piston *c*, the pistons *c* and *d* being shifted owing to this lack of balance to bring the piston *d* into a position to uncover more or less the 65 air exit ports *n*, thus permitting the air at one side of the brake piston to escape to the atmosphere and thus cause movement of the brake piston to apply the brakes. Should the train pipe pressure be completely reduced, as in emergency application of the 70 brakes, these ports *n* are completely uncovered and allow a total discharge of air from the brake cylinder, bringing the full braking force into action; but should, on the 75 other hand, said train pipe pressure be only partially reduced momentarily, then the air after actuating the smaller piston *d* discharges through the ports *n* until the opposing pressures acting on both pistons are 80 equalized, the pressure acting on the larger piston *c* then operating to return the small piston *d* to a position where it will cover and close the air escape ports *n*, and further reduction in the pressure of air in the brake 85 cylinder is thereby prevented.

In order to release the brakes more air is charged into the train pipe, such air being fed through the tubular piston rod into the 90 brake cylinder, and any desired reduction of brake power can be made by suitable variation of the air pressure charged into train pipe.

The respective pistons although on the same rod work in two cylinders as *e* and *f* of different diameters and are connected up in tandem manner as shown. It may also be stated that the device forms or acts as a governor and is interposed in the branch pipe between the brake cylinder and train pipe. 95

What I claim as my invention and desire 100 to secure by Letters Patent is—

In an air brake apparatus, a brake controlling air escape valve comprising a casting having cylinders of larger and smaller diameters adapted to be connected respectively to the train pipe and the brake cylinder, the cylinder of smaller diameter having a plurality of circumferentially spaced air escape ports in the lateral wall thereof, and 110

pistons of different diameters operating in said cylinders and having a hollow rod connecting them and forming a conduit for feeding air between opposite ends of the 5 pistons, the larger piston having its active face subject to the pressure of air in the train pipe and the smaller piston operating to simultaneously open or close all of said air escape ports in its movements and being

subject to the pressure of air in the brake 10 cylinder.

In testimony whereof I have hereunto set my hand in presence of two subscribing witnesses.

SAMUEL CHENEY.
